ELECTRIC LIGHTING DEVICE

Harry A. Douglas, Bronson, Mich., assignor to
Kingston Products Corporation, a corporation
of Indiana

Application April 4, 1936, Serial No. 72,780

35 Claims. (Cl. 240—41)

My invention relates to electric lighting devices, and more particularly to electric lamp units comprising an incandescent electric lamp mounted in a reflector, as for example, in an automobile headlight, and the principal object of my invention is to provide a new and improved lighting device and unit of this type.

In the drawings accompanying this specification, and forming a part of this application, I have shown, for purposes of illustration, several forms which my invention may assume. In these drawings:

Figure 1 is a vertical sectional view, certain parts being fragmentarily shown, of one embodiment of my invention.

Figure 2 is a fragmentary rear elevation of a detail of Figure 1.

Figure 3 is a front elevation of a detail.

Figure 4 is a section taken on the line 4—4 of Figure 3, looking in the direction of the arrows.

Figure 5 is a front elevation, partly in section, of a lamp used in the embodiment of Figure 1.

Figure 6 is a fragmentary front elevation of a mounting or reflector used in the embodiment of Figure 1.

Figure 7 is a section taken on the line 7—7 of Figure 1, looking in the direction of the arrows.

Figure 8 is a fragmentary sectional view taken on the line 8—8 of Figure 7, looking in the direction of the arrows.

Figure 9 is a fragmentary sectional view taken on the line 9—9 of Figure 7, looking in the direction of the arrows.

Figure 10 is a vertical sectional view, certain parts being fragmentarily shown, of another embodiment of my invention.

Figure 11 is a front elevation, partly in section, of a lamp used in the embodiment of Figure 10.

Figure 12 is a fragmentary front elevation of a mounting or reflector used in the embodiment of Figure 10.

Figure 13 is a section taken on the line 13—13 of Figure 10, looking in the direction of the arrows.

Figure 14 is a fragmentary sectional view taken on the line 14—14 of Figure 13, looking in the direction of the arrows.

Figure 15 is a vertical sectional view, certain parts being fragmentarily shown, of another embodiment of my invention, along with a side elevation of a line connector which may be used in said embodiment.

Figure 16 is a front elevation, partly in section, of a lamp used in the embodiment of Figure 15.

Figure 17 is a fragmentary rear elevation of a detail of the lamp of Figure 16.

Figures 18 and 19 are sections taken respectively on the lines 18—18 and 19—19 of Figure 15, looking in the direction of the arrows.

Figure 20 is a fragmentary front elevation of a mounting or reflector used in the embodiment of Figure 15.

Figure 21 is a section taken on the line 21—21 of Figure 15, looking in the direction of the arrows.

Figure 22 is a fragmentary sectional view taken on the line 22—22 of Figure 21, looking in the direction of the arrows.

Figure 23 is a vertical sectional view, certain parts being fragmentarily shown, of another embodiment of my invention.

Figure 24 is a front elevation, partly in section, of a lamp used in the embodiment of Figure 23.

Figure 25 is a fragmentary front elevation of a mounting or reflector used in the embodiment of Figure 23.

Figure 26 is a section taken on the line 26—26 of Figure 23, looking in the direction of the arrows.

Figure 27 is a fragmentary sectional view taken on the line 27—27 of Figure 26, looking in the direction of the arrows.

Figure 28 is a side elevation of the lamp shown in Figure 24, assembled with a line connector or contact carrier.

Figure 29 is a fragmentary sectional view taken on the line 29—29 of Figure 26, looking in the direction of the arrows, and

Figure 30 is a front elevation of a line connector or contact carrier which may be used in the embodiment of Figure 23.

Referring to Figure 1, the embodiment of my invention here illustrated is shown as including an incandescent electric lamp 40, adapted to be suitably connected to a mounting, the mounting being in this instance a reflector 41 fragmentarily shown. The lamp 40 is provided with a base 42, having a shell 43, which in this instance includes a lateral extension 44 comprising positioning means 45 combined with a biasing means 46 for biasing the positioning means 45 against the mounting 41. The positioning means 45 is adapted to abut the front surface of the reflector 41, whereas the biasing means is adapted to abut a rear surface of the reflector, as will more fully appear. By front is meant that side of a part presented toward the light producing source of the lamp 40 and by rear the opposite side. The lateral extension 44 of the base comprises a collar 55

47 surrounding the shell 43 and a radially extending flange 48 on the collar. The collar 47 may be fastened to the shell 43 in any suitable manner, as by solder 49. The flange 48 is here shown as continued radially outwardly in the form of three sectoral projections 50, 51, 52 (forming part of the positioning means 45), unequally circumferentially spaced, the axes of symmetry of the upper sectoral projections, 51, 52, as viewed in Figure 5, being here shown as less than 120° apart, and the axis of symmetry of the lower sectoral projection, 50, approximately bisecting the angle between the axes of symmetry of the upper sectoral projections, 51, 52. The peripheral arcs of the sectoral projections 50, 51, 52 define a circle, and are here shown as unequal, the peripheral arc of the sectoral projection 52 being the smallest, and that of the sectoral projection 51 being larger, and that of the sectoral projection 50 being the largest. Here shown as spaced circumferentially equal distances from the nearest margins of the sectoral projections 51, 52, are axially rearwardly extending projections 53, conveniently formed by making indentations 54 on the front surfaces of the sectoral projections. The lower sectoral projection, 50, is also provided with an axially rearwardly extending projection 53, here shown as located on a line approximately bisecting the angle between, and as concyclic with the two other axial projections 53.

Offset rearwardly and interposed circumferentially between the sectoral projections 50, 51, 52 are three resilient fingers 55, 56, 57, forming part 35 of the biasing means 46, integrally joined to the flange 48 by connecting portions 58. The outer peripheries of the fingers 55, 56, 57 are here shown as defining a circle of the same diameter as that defined by the positioning means 45. The outer ends of the fingers 55, 56, 57 are of generally sectoral form, as here shown, and the axes of symmetry of the lower fingers, 55, 57, are spaced more than 120° apart, and the axis of symmetry of the upper finger, 56, approximately bisects the angle between the axes of symmetry of the lower fingers, 55, 57. The lower fingers, 55, 57, are of the same general width circumferentially, whereas the width of the upper finger, 56, is somewhat less. The upper finger, 56, is here shown as provided with a forwardly extending dome-shaped projection or detent 59, conveniently formed by making an indentation 60 in the opposite side of the finger. This detent 59 is approximately circumferentially half-way 55 between the axial projections 53. Spaced at approximately equal angles clockwise and counter-clockwise from the axial projection 53 on the lower sectoral projection, 50, the fingers 55, 57 are here shown as respectively provided with 60 dome-shaped forwardly extending detents 59, identical with the detent 59 of the finger 56. The detents 59 are here shown as concyclic with each other and with the axial projections 53.

One of the fingers, 57, is here shown as provided with a lug 105 bent forwardly out of a lateral margin of the finger.

The lamp 40 is here shown as provided with a pair of butt-type contacts 61, 62 which are co-operable with a pair of contacts 63, 64 on a contact carrier 65. The contact carrier 65 is here shown as comprising a generally cylindrical shell 66 provided at its front end with a radially extending generally annular flange 67 having unequally circumferentially spaced arms 68 extending in a generally radial direction from its periph-

ery. The arms 68 are provided with axially frontwardly extending arcuate portions 69, these arcuate portions defining a cylinder. The free ends of the arcuate portions 69 are formed into hooks 70, 71, 72. One of the hooks, 71, is most clearly shown in Figure 4, and as these hooks 70, 71, 72 are all identical, a description of one of them will serve for all. The hook 71 has a throat 73, narrower than the circumferential width of the arcuate portion 69. The bottom 74 of the mouth 75 of the hook is V-shaped, formed by margins 76, 77 meeting at an angle. The free end of the throat of the hook is here shown as formed by a beveled margin 78, and the lip of the hook also has a beveled margin 79. The chin of the hook may also have a beveled margin 80.

The contact carrier 65 includes an insulating member 81 having an outside diameter such as to fit within the shell 66, and having three circumferentially spaced radial projections 82, 83, 84 adapted to fit three axially extending recesses 85, 86, 87 in the rear end of the shell. The projection 82 and recess 85 may be larger than the other projections, 83, 84, and recesses, 86, 87, so that the insulating member 81 may be assembled with the shell 66 in but one relative rotative relation. In order to hold the insulating member 81 assembled with the shell 66 a plurality of fingers 88, in this instance four, extending rearwardly from the shell 66, may be provided, and clinched 30 radially inwardly over the rear face of the insulating member.

The insulating member 81 carries the contacts 63, 64, these contacts being desirably formed as enlarged heads on shanks fitted over and swedged 35 to the ends of conductors 89, 90 respectively. The conductors 89, 90 are disposed in sleeves, each sleeve 91 being slidable within a bushing 92, which is fixedly mounted, in any suitable manner, as by beading, on the insulating member 81. Each 40 sleeve 91 is surrounded by a spring 93 between its bushing and a flange 94 on each sleeve abutting the respective contacts 63, 64.

The contacts 63, 64 are adapted to make contact respectively with the contacts 61, 62 on the lamp base when the contact carrier 65 is assembled with the reflector 41, as shown in Figure 1. The springs 93 serve to bias the hooks 70, 71, 72 into cooperative relation with the reflector.

The provision of a plurality of contacts 61, 62 on the lamp enables the use of a multiple filament lamp, the lamp being here shown as provided with two filaments, one of which, 95, may desirably have its lighting center at some predetermined point with respect to the reflector, as for example 55 at the focus, and the other of which, 96, may be displaced from the filament 95, and may be used for providing dim or so-called tilted light. The filaments 95, 96 have their terminals connected in a well known manner to the lamp base shell 60 43 and to the contacts 61, 62 on the lamp base. The passage of current to either one or both of the filaments 95, 96 may be controlled in any suitable manner, as by switching means (not shown) interposed in the conductors 89, 90. 65

The reflector 41 is here shown as provided with a rearwardly extending pocket 97 having a cylindrical portion 98 terminating in a flat end flange 99. The diameter of the inner periphery of the cylindrical portion 98 is here shown as such that it will gage, that is, snugly fit, the outer peripheries of the sectoral projections 50, 51, 52 of the positioning means 45, when the axial projections 53 are in abutment with the front face of the end flange 99, as shown in Figure 1. The end flange 75

99 of the reflector is here shown as provided with a central aperture 100, and there are three recesses 101, 102, 103 extending radially outwardly from the margin of the aperture 100, to the inner periphery of the cylindrical portion 98. The recesses 101, 103 are here shown as more than 120° apart, to the same angle as the fingers 55, 57, and the axis of symmetry of the recess 102 approximately bisects the angles between the axes of symmetry of the recesses 101, 103. The recesses 101, 102, 103 are so proportioned and so located that the sectoral ends of the fingers 55, 56, 57 will be able to pass through these recesses, and pass through them in but one relative rotative relation with respect to the reflector 41. The end flange 99 is here shown as provided with three recesses or apertures 104 for cooperation with the detents 59 of the fingers 55, 56, 57. For cooperation with the hooks 70, 71, 72 of the contact carrier 65, the reflector 41 is here shown as provided with three compound arcuate apertures 106, 107, 108, in this instance disposed in the curved portion of the reflector 41, radially outside of the pocket. Each of the compound apertures 106, 107, 108 includes a larger, entrance portion 109 and a smaller portion 110, spaced circumferentially from the entrance portion 109 to form a seat 111 for the respective cooperating hook. The compound apertures 106, 107, 108 are here shown as of the same radial extent as that of the thickness of the hooks.

The contact carrier 65 may be assembled with the reflector 41 by inserting the hooks 70, 71, 72 through the entrance portions 109 of the compound apertures 106, 107, 108 and rotating the contact carrier 65 slightly clockwise, as viewed from the rear of the reflector, until the parts are brought to the position shown in Figures 1, 7, and 9, in which the margins of the seats 111 are engaged by the margins 76, 77 of the bottoms of the mouths of the hooks 70, 71, 72.

The lamp 40 may be assembled with the reflector 41 as follows. The lamp 40 is brought to a position coaxial with the aperture 100 of the reflector, at the front of the reflector, with its base presented toward the reflector. The lamp is then moved axially rearwardly, and is so positioned rotationally, that the fingers 55, 56, 57 will pass through the recesses 101, 102, 103, against the bias of the springs 93. The lamp 40 is then moved further axially, the fingers 55, 56, 57 passing through the recesses 101, 102, 103 and the axial projections 53 coming into contact with the front surface of the reflector end flange 99. The lamp 40 is then rotated clockwise, as viewed from the front of the reflector, thereby causing the detents 59 to engage the leading margins of the recesses 101, 102, 103. Further clockwise rotation causes the detents 59 to ride up onto the rear surface of the end flange 99 and eventually to snap into the apertures 104, bringing the parts to the position shown in Figure 7, in which the lug 105 is in engagement with a radial margin of the recess 103. It will be understood that when the detents 59 are seated on the margins of the apertures 104 in the position shown in Figures 1, 7, and 8, the fingers 55, 56, 57 are under sufficient stress to hold the axial projections 53 of the positioning means 45 in firm engagement with the front face of the end flange 99.

The mode of disassembly of the lamp from the reflector will be obvious from the foregoing description of the mode of assembly.

The fingers 55, 57 may be made slightly wider circumferentially than the finger 56 so as to more

nearly equalize the biasing action of the fingers on the axial projections 53.

The seats 111 are here shown as so positioned that when the lamp is mounted on the reflector 41 the axial projections 53 are in radial alignment with the seats 111.

Since the positioning means 45 is accurately pre-positioned with respect to its distance from the filaments 95, 96, and the direction of the plane of the positioning means 45 is accurately pre-positioned with respect to the axis of the lamp 40, and furthermore, since the construction provides for predetermining the position of the lamp about its axis with respect to the reflector, the filament 95 and also the auxiliary filament 96 will be positioned at the desired places with respect to the reflector. It will be furthermore noted that, due to the unequal circumferential spacing of the hooks 70, 71, 72 and the corresponding spacing of the compound apertures 106, 107, 108, the contact carrier 65 may be assembled with the reflector 41, and therefore with the lamp 40, in but one relative rotative relation.

The positioning means 45 may be pre-positioned with respect to the lamp 40 by placing the positioning means on a standard, with the shell 43 within the collar 47 and then adjusting the lamp until the lighting center of the desired filament is in a predetermined position, whereupon the collar is soldered to the shell 43. The position of the other filament of the lamp may be likewise simultaneously predetermined.

Referring to Figure 10, the embodiment of my invention here illustrated is shown as including an incandescent electric lamp 40a, adapted to be suitably connected to a reflector 41a fragmentarily shown. The lamp 40a is provided with a base 42a, having a shell 43a, which in this instance includes a lateral extension 44a comprising a positioning means 45a combined with a biasing means 46a for biasing the positioning means against the mounting. The positioning means 45a is adapted to abut a rear surface of the reflector 41a whereas the biasing means is 45 adapted to abut a front surface of the reflector 41a, as will more fully appear. The lateral extension 44a of the base comprises a collar 47a surrounding the shell 43a, and a radially extending flange 48a on the collar 47a. The collar 47a may be fastened to the shell 43a in any suitable manner, as by solder 49a. The flange 48a is here shown as continued radially outwardly in the form of three sectoral projections 112, 113, 114 (forming part of the positioning means 45a), 55 unequally circumferentially spaced and as of unequal circumferential extent. Extending axially rearwardly from the sectoral projections 112, 113, 114 are three arcuate flanges 115, the outer peripheries of which define a cylinder. Extending 60 radially outwardly from the rear margins of the arcuate flanges 115 are three secondary sectoral projections 116, 117, 118. The radial axes of symmetry of the secondary sectoral projections 116, 118 are here shown as less than 120° apart and 65 the radial axis of symmetry of the projection 117 approximately bisects the angle between the axes of symmetry of the projections 116, 118. The peripheral arcs of the secondary sectoral projections 116, 117, 118 define a circle, and are here 70 shown as not all equal, the peripheral arcs of the projections 116, 118 being equal, and that of the projection 117 being the larger than that of either of the other two. Here shown as centrally disposed on the secondary sectoral projections 75

116, 117, 118 are axially frontwardly extending projections 53a, conveniently formed by making indentations 54a on the rear surfaces of the projections 116, 117, 118. One of the secondary 5 sectoral projections, 118, is provided with a frontwardly extending lug 105a, on its right hand margin, as viewed in Figure 11.

In the general plane of and integral with the flange 48a and interposed circumferentially between the sectoral projections 112, 113, 114 are three radially extending fingers 55a, 56a, 57a. These fingers are here shown as of uniform width, and desirably have arched portions 119 to increase their actual length, though their radial 10 length is such that their peripheral margins are in the circle defined by the outer peripheries of the secondary sectoral projections 116, 117, 118. As here shown, the axes of symmetry of the fingers 55a, 57a are spaced less than 120° apart, to 15 the same angle as the axes of symmetry of the secondary sectoral projections 116, 118, and the axis of symmetry of the finger 56a approximately bisects the angle between the axes of symmetry of the other fingers, 55a, 57a. The fingers 55a, 20 56a, 57a are here shown as provided with centrally located rearwardly extending dome-shaped projections or detents 59a, conveniently formed by making indentations 60a in the opposite sides of the fingers. The detents 59a are here shown 25 as concyclic with each other and with the axial projections 53a.

The lamp 40a is here shown as provided with a pair of butt-type contacts 61a, 62a which are co-operable with a pair of contacts 63a, 64a on a 30 contact carrier 65a. The contact carrier 65a is identical with the contact carrier 65 of the embodiment of Figures 1 through 9, except that when connected to the reflector 41a the hooks 70a, 71a, 72a are disposed 180° from the position 35 assumed by the hooks 70, 71, 72 of the contact carrier 65.

The reflector 41a is here shown as provided with a flat portion 120. The diameter of the flat portion 120 is here shown as approximately the 40 same as the diameter of the outer periphery of the lamp base extension 44a. The flat portion 120 of the reflector is here shown as provided with a central aperture 100a, of such diameter as will gage the peripheral surfaces of the arcuate flanges 50 115. Three recesses 121, 122, 123 are provided, extending radially outwardly from the margin of the aperture 100a, to the outer periphery of the flat portion 120. The recesses 121, 123 are here shown as less than 120° apart, to the same angle 55 as the sectoral projections 116, 118, and the axis of symmetry of the recess 122 approximately bisects the angle between the axes of symmetry of the recesses 121, 123. The recesses 121, 122, 123 are so proportioned and so located that the secondary 60 sectoral projections 116, 117, 118 will be able to pass through these recesses, and pass through them in but one relative rotative relation with respect to the reflector 41a. The flat portion 120 is here shown as provided with three recesses or apertures 104a for cooperation with the detents 59a of the fingers 55a, 56a, 57a. For 65 cooperation with the hooks 70a, 71a, 72a of the contact carrier the reflector is here shown as provided with three compound apertures 106a, 107a, 108a, identical with the compound apertures 106, 107, 108 of the reflector 41 shown in Figure 6, but so located that they will accommodate the hooks 70a, 71a, 72a of the contact carrier 65a in its position hereinbefore noted.

70 75 The lamp 40a may be assembled with the re-

flector 41a as follows. The lamp 40a is brought to a position coaxial with the aperture 100a of the reflector, at the front of the reflector, with its base presented toward the reflector. The lamp 40a is then moved axially rearwardly, and is so 5 positioned rotationally, that the secondary sectoral projections 116, 117, 118 will pass through the recesses 121, 122, 123, against the bias of the springs 93a. The lamp 40a is then moved further axially, the projections 116, 117, 118 passing 10 through recesses 121, 122, 123, and the arcuate flanges 115 slipping into the aperture 100a, and the detents 59a coming into contact with the front surface of the flat portion 120 of the reflector. The lamp 40a is then moved rearwardly 15 slightly, if that is necessary to cause the secondary sectoral projections 116, 117, 118 to clear the rear surface of the flat portion 120, and the lamp is then rotated clockwise, as viewed from the front of the reflector, thereby causing the 20 axial projections 53a to ride onto the rear surface of the flat portion 120, and eventually causing the detents 59a to snap into the apertures 104a, bringing the parts to the position shown in Figures 10, 13, and 14, in which the lug 105a is in engagement 25 with a radial margin of the recess 123. It will be understood that when the detents 59a are seated on the margins of the apertures 104a in the position shown in Figures 10, 13, and 14, the fingers 55a, 56a, 57a are under sufficient stress to hold 30 the axial projections 53a of the positioning means 45a in firm engagement with the rear face of the flat portion 120.

As here shown the seats 111a are so located 35 that when the lamp is assembled with the reflector, the axial projections 53a of the positioning means will be in radial alinement with the seats 111a.

For reasons already pointed out in connection with the embodiment of Figure 1, it will be 40 evident that the filaments 95a, 96a of the lamp 40a will be accurately positioned with respect to the reflector 41a, and the contact carrier 65a will bear the desired rotative relation to the reflector and lamp, when the parts are assembled as 45 shown in Figures 10, 13, and 14.

Referring to Figure 15, the embodiment of my invention here illustrated is shown as including an incandescent electric lamp 40b, adapted to be 50 suitably connected to a reflector 41b, fragmentarily shown. The lamp 40b is provided with a base 42b, having a shell 43b, which in this instance also includes a lateral extension 44b comprising a positioning means 45b combined with a biasing means 46b for biasing the positioning 55 means against the reflector. In this instance the positioning means 45b is adapted to abut a front surface of the reflector 41b and the biasing means is adapted to abut a rear surface of the reflector. The lateral extension 44b comprises a collar 47b 60 surrounding the shell 43b and a radially extending flange 48b on the collar. The flange 48b is here shown as continued radially outwardly in the form of three sectoral projections 124, 125, 126, here shown as unequally circumferentially 65 spaced and as of unequal circumferential extent. Extending radially outwardly from the outer peripheries of the sectoral projections 124, 125, 126 are three secondary sectoral projections 127, 128, 129. The axes of symmetry of the secondary 70 sectoral projections 127, 129 are spaced more than 120° apart and the axis of symmetry of the secondary sectoral projection 128 approximately bisects the angle between the axes of symmetry of the other secondary sectoral projections 127, 129. 75

The peripheral arcs of the secondary projections 127, 128, 129 define a circle. The peripheral arcs of the projections 127, 129 are equal, and that of the projection 128 is smaller than either of the other two. Here shown as disposed equal distances from one of the margins of the respective secondary sectoral projections 127, 128, 129 are axially rearwardly extending projections 53b, conveniently formed by making indentations 54b in the front surfaces of the projections 127, 128, 129.

Offset rearwardly and interposed circumferentially between the sectoral projections 124, 125, 126 are three radially extending fingers 55b, 56b, 57b integrally joined to the flange 48b by connecting portions 58b. The outer ends of the fingers 55b, 56b, 57b are of sectoral form, corresponding to the secondary sectoral projections 127, 128, 129. As here shown, the axes of symmetry of the fingers 55b, 57b are spaced more than 120° apart, to the same angle as the axes of symmetry of the secondary sectoral projections 127, 129, and the axis of symmetry of the finger 56b approximately bisects the angle between the axes of symmetry of the other fingers 55b, 57b. The lower fingers, 55b, 57b, are generally of the same width circumferentially, whereas the width of the upper finger 56b is somewhat less. Here shown as disposed equal distances from one of the margins respectively of the sectoral ends of the fingers 55b, 56b, 57b are frontwardly extending dome-shaped projections or detents 59b, conveniently formed by making indentations 60b in the opposite sides of the fingers. The detents 59b are here shown as concyclic with each other and with the axial projections 53b.

In order to make electrical connection with the lamp 40b, the lamp is here shown as provided with a pair of contacts 130, 131 in the form of spaced, axially extending plug terminals, of the snap type; and these plug terminals 130, 131 are here shown as of different cross-sectional diameter, but otherwise similar. Each plug terminal has a frustro-conical end portion 132 and an annular furrow 133 spaced somewhat from the frustro-conical end portion 132. Cooperable with the plug terminals 130, 131 is a line connector 134 of insulating material in which are disposed two sleeves 135, 136, as may be seen in Figure 18, the inside diameters of which correspond respectively to the outside diameters of the plug terminals 130, 131, and which are spaced to cooperate with the plug terminals. Each conducting sleeve 135, 136 may be provided with a detent 137, struck inwardly from each sleeve, these detents being spaced from the left hand end of the connector 134, as viewed in Figure 15, and so designed that when the plug terminals 130, 131 are pushed into the left hand end of the line connector 134 the detents 137 will resiliently yield and slide up the frustro-conical end surfaces 132 of the respective plug terminals, and then snap into the annular furrows 133. The right hand end of the line connector 134 is here shown as provided with a pair of conducting sleeves 138 of the same diameter, and these sleeves may be respectively integral with the sleeves 135, 136 at the left hand end. The sleeves 138 at the right hand end may also be provided with detents 139 struck in from the sleeves and are thus cooperable with plug conductor terminals of the snap type, similar to those provided on the lamp base. The filaments 95b, 96b of the lamp 40b may be connected to the base 42b and to the lamp contacts 130, 131, and 75 may be controlled in a manner as already de-

scribed in connection with the lamp 40 and its contacts 61, 62.

The reflector 41b is identical with the reflector 41 shown in Figure 6, with the exception that it is not provided with compound apertures such as the apertures 106, 107, 108. The central aperture 100b of the reflector 41b is of such diameter as will permit the circle-defining peripheral margins of the sectoral projections 124, 125, 126 to pass therethrough, and the inner periphery of the cylindrical portion 98b of the reflector pocket 97b is such as will gage the circle defined by the outer peripheries of the secondary sectoral projections 127, 128, 129 when the axial projections 53b are in abutment with the front surface of the end flange 99b.

Assuming that the line connector 134 is connected to the contacts 130, 131 of the lamp 40b and the lamp has been disassembled from the reflector 41b, the line connector 134 and its connected conductors (not shown) having been pulled through the aperture 100b of the reflector, a new lamp may be plugged into the line connector 134, if desired, and the lamp, such as 40b, is then brought to a position co-axial with the aperture 100b. The lamp 40b is then moved axially rearwardly, and is rotationally so positioned that the sectoral ends of the fingers 55b, 56b, 57b will pass through the recesses 101b, 102b, 103b. Axial rearward movement is then continued until the axial projections 53b abut the front surface of the end flange 99b of the reflector. The lamp 40b is then rotated clockwise, as viewed from the front of the reflector, thereby causing the detents 59b to engage the leading margins of the recesses 101b, 102b, 103b. Further clockwise rotation causes the detents 59b to ride up onto the rear surface of the end flange 99b and eventually to snap into the apertures 104b, bringing the parts to the position shown in Figures 15, 21, and 22. Here also it will be understood that when the detents 59b are seated on the margins of the apertures 104b the fingers 55b, 56b, 57b are under sufficient stress to hold the axial projections 53b of the positioning means 45b in firm engagement with the front surface of the end flange 99b.

Assuming that the lamp 40b is disassembled from the reflector 41b and is positioned at the rear thereof and it is desired to assemble it with the reflector, the lamp is brought to a position coaxial with the aperture and moved axially frontwardly, bulb first, the lamp being rotationally so positioned that the secondary sectoral projections 127, 128, 129 will pass through the recesses. Frontward axial movement is continued until the detents 59b abut the rear surface of the end flange 99b, and in case the positioning means 45b is not sufficiently far forward to clear the end flange 99b, this may be brought about by moving the lamp frontwardly slightly to put the biasing means 46b under stress. The lamp is then rotated in a clockwise direction, as viewed from the rear of the reflector, thereby causing the axial projections 53b to ride onto the front surface of the end flange 99b. Further rotation of the lamp 40b will cause the detents 59b to snap into the apertures 104b, the parts then again assuming the position shown in Figures 15, 21, and 22.

It will be evident from the foregoing that the lamp 40b may be assembled with, and accurately positioned with respect to the reflector 41b by approach from either the front or the rear of the reflector; and from the assembled position, as shown in Figures 15 and 21, it may be disassem-

bled from the reflector by either withdrawing it frontwardly or rearwardly, irrespective of whether it has been assembled with the reflector by approach from the front or rear.

5 Referring to Figure 23, the embodiment of my invention here illustrated is shown as including an incandescent electric lamp 40c, adapted to be suitably connected to a reflector 41c fragmentarily shown. The lamp is provided with a base 42c, having a shell 43c, which in this instance also includes a lateral extension 44c, comprising positioning means 45c combined with a biasing means 46c for biasing the positioning means against the reflector. The lateral extension 44c 10 comprises a collar 47c surrounding the shell 43c and a radially extending flange 48c on the collar. The collar 47c may be fastened to the shell 43c in any suitable manner, as by solder 49c. The flange 48c is here shown as continued radially outwardly in the form of three sectoral projections 140, 141, 142 (forming part of the positioning means 45c), here shown as unequally circumferentially spaced, and as of unequal circumferential extent. Extending axially rearwardly 15 from the sectoral projections 140, 141, 142 are three arcuate flanges 143, the outer peripheries of which define a cylinder. Extending radially outwardly from the rear margins of the arcuate flanges 143 are three secondary sectoral projections 144, 145, 146. The radial axes of symmetry of the secondary sectoral projections 144, 146 are here shown as less than 120° apart and the radial axis of symmetry of the projection 145 approximately bisects the angle between the axes of symmetry of the projections 144, 146. The peripheral arcs of the secondary sectoral projections 144, 145, 146 define a circle. The peripheral arc of the sectoral projections 144, 146 are equal, and that of the projection 145 is larger than either 20 of the other two (144, 146). Here shown as centrally located on the secondary sectoral projections 144, 145, 146 are axially frontwardly extending projections 53c, conveniently formed by making indentations 54c on the rear surfaces of 25 the projections 144, 145, 146.

In the general plane of and integral with the flange 48c, and interposed circumferentially between the sectoral projections 140, 141, 142 are three radially extending fingers 55c, 56c, 57c. 30 These fingers are here shown as of uniform width, and desirably have arched portions 119c to increase their actual length, though their radial length is such that their peripheral margins are in the circle defined by the outer peripheries of the secondary sectoral projections 144, 145, 146. It will be evident that if desired the ends of the fingers 55c, 56c, 57c may be made of sectoral form to correspond to the secondary sectoral projections 144, 145, 146, analogously to the relation between the ends of the fingers 55b, 56b, 57b, and the secondary sectoral projections 127, 128, 129.

As here shown, the axes of symmetry of the 40 fingers 55c, 57c are spaced less than 120° apart, to the same angle as the axes of symmetry of the secondary sectoral projections 144, 146, and the axis of symmetry of the finger 56c approximately bisects the angle between the axes of symmetry of the other fingers, 55c, 57c. The fingers 55c, 56c, 57c are here shown as provided with centrally located rearwardly extending dome-shaped projections or detents 59c conveniently formed by making indentations 60c in the opposite sides 45 of the fingers. The detents 59c are here shown

as noncyclic with each other and with the axial projections 53c.

The lamp is here shown as provided with a pair of butt-type contacts 61c, 62c which are co-operable with a pair of contacts 63c, 64c on a 5 contact carrier 148. The contact carrier 148 is here shown as comprising a generally cylindrical shell 149 provided at its front end with unequally circumferentially spaced hooks 150, 151, 152, the inner and outer peripheral surfaces of which are, in this instance, extensions of the surfaces of the shell 149. One of the hooks is shown in detail in Figure 27, and as these hooks are similar to the hooks 70, 71, 72 of the contact carrier 65, differing therefrom 10 merely in size, no further description is necessary.

The contacts 63c, 64c of the contact carrier 148 are spring pressed and constructed and arranged just as are the contacts 63, 64 of the contact carrier 65 of the embodiment of Figure 1. 20

For cooperation with the hooks 150, 151, 152, the flange 48c is here shown as provided with three unequally circumferentially spaced compound apertures 153, 154, 155, similar to the compound apertures 107, 108, 109 in the reflector 41 25 of the embodiment of Figure 1. It will be apparent that the hooks 150, 151, 152 may be inserted through the entrance portions of the corresponding apertures 153, 154, 155 against the bias of the springs 93c, and brought into cooperative relation with the seats of the compound apertures, as shown in detail in Figure 27, in a manner analogous to that described in connection with the hooks 70, 71, 72 and the apertures 106, 107, 108. Thus, in the embodiment of Figure 23 the contact carrier 148 will be carried by the lamp 40c.

The reflector 41c is identical with the reflector 41a (shown in Figure 12) of the embodiment of Figure 10, with the exception that no compound apertures such as 106a, 107a, 108a are necessary, and also, apertures 104c, for cooperation with the detents 59c, are disposed, differently than the apertures 104a, to accommodate the change in relation as between the positioning means 45c and biasing means 46c on the one hand, and the positioning means 45a and biasing means 46a on the other. The relation of the recesses 121c, 122c, 123c to the set of fingers 55c, 56c, 57c and to the set of secondary sectoral 50 projections 144, 145, 146 is such that each of these sets may be passed through these recesses in but one relative rotative relation with respect to the reflector.

The lamp 40c may be assembled with the reflector 41c, by approach from the front of the reflector, as follows. The lamp 40c is brought to a position coaxial with the aperture 100c of the reflector 41c, at the front of the reflector, with its base presented toward the reflector. The lamp is then moved axially rearwardly, and is so positioned rotationally, that the secondary sectoral projections 144, 145, 146 will pass through the recesses 121c, 122c, 123c. The lamp is then moved further axially, the projections 144, 145, 146 passing through recesses 121c, 122c, 123c, and the arcuate flanges 143 slipping into the reflector aperture 100c, and the detents 59c coming into contact with the front surface of the flat portion 120c of the reflector. If necessary 70 to bring the secondary sectoral projections 144, 145, 146 to a position of axial clearance with respect to the rear face of the flat portion 120 of the reflector, the fingers 55c, 56c, 57c may be put under a slight stress by pressing the lamp 75

rearwardly, and the lamp is then rotated clockwise, as viewed from the front of the reflector, thereby causing the axial projections 53c to ride onto the rear surface of the flat portion 120c of the reflector, and eventually causing the detents 59c to snap into the apertures 104c, bringing the parts to the position shown in Figures 23, 26, and 29, in which the filaments 95c, 96c will be accurately positioned with respect to the reflector 41c, as will be apparent. It will be understood that when the detents 59c are seated on the margins of the apertures 104c in the position of the parts shown in Figures 23, 26, and 29, the fingers 55c, 56c, 57c are under sufficient stress to hold the axial projections 53c of the positioning means in firm engagement with the rear face of the flat portion 120c of the reflector.

The lamp 40c may be assembled with the reflector 41c by approach from the rear of the reflector, as follows. The lamp is brought to a position coaxial with the aperture 100c, at the rear of the reflector and is then moved, bulb first, frontwardly, and is rotationally so positioned that the fingers 55c, 56c, 57c will pass through the recesses 121c, 122c, 123c. Axial frontward movement is then continued, the arcuate flanges 143 slipping into the reflector aperture 100c, until the axial projections 53c abut the rear surface of the flat portion 120c of the reflector. The lamp is then rotated clockwise, as viewed from the rear of the reflector thereby causing the detents 59c to engage the leading margins of the recesses 121c, 122c, 123c. Further clockwise rotation causes the detents 59c to ride up onto the front surface of the flat portion 120c and eventually to snap into the apertures 104c, bringing the parts to the position shown in Figures 23, 26, and 29.

It will be evident from the foregoing that, as in the case of the lamp 40b of the embodiment of Figure 15, the lamp 40c may be assembled with the reflector 41c by approach from either the front or the rear of the reflector; and from the assembled position, as shown in Figures 23 and 26, it may be disassembled from the reflector by either drawing it frontwardly or rearwardly, irrespective of whether it has been assembled with the reflector by approach from the front or rear. Also the contact carrier 148 may be manipulated in a manner analogous to that already set forth in connection with the line connector 134 of the embodiment of Figure 15.

From the foregoing it will be apparent to those skilled in the art that each of the illustrated embodiments of my invention provides a new and improved electric lighting device and unit, readily and conveniently constructed and assembled, and accordingly, each accomplishes the principal object of my invention. On the other hand, it also will be obvious to those skilled in the art that the illustrated embodiments of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

70 I claim:

1. In combination: an incandescent electric lamp having a base; mounting means for said lamp; laterally extending positioning means on said base, constructed and arranged to abut said mounting; biasing means constructed and ar-

ranged to press said positioning means into abutment with said mounting; said positioning means and said biasing means being constructed integral with each other from a single sheet metal stamping.

2. In combination: an incandescent electric lamp having a base; mounting means for said lamp; laterally extending positioning means on said base, constructed and arranged to abut said mounting at one side thereof; biasing means constructed and arranged to abut the other side of said mounting and to press said positioning means into abutment with said mounting; said positioning means and said biasing means being constructed integral with each other from a single sheet metal stamping.

3. An incandescent electric lamp, comprising: a base having a lateral extension for abutting a mounting, said lateral extension including two sets of circumferentially spaced radially extending projections, said sets being in different planes and having a predetermined angular relation with each other.

4. In combination: an incandescent electric lamp having a base; mounting means for said lamp, said mounting means having an aperture having a plurality of circumferentially spaced radially extending recesses; laterally extending positioning means unitary with said base, abutting said mounting at one side thereof; biasing means unitary with said base, having portions insertable through said recesses and abutting said mounting at the other side thereof circumferentially between said recesses, constructed and arranged to press said positioning means into abutment with said mounting; and said positioning means and said biasing means being integral with each other.

5. In combination: an incandescent electric lamp having a bulb and a base; mounting means for said lamp, said mounting means having an aperture having a plurality of circumferentially spaced radially extending recesses; laterally extending positioning means unitary with said base, having portions insertable through said recesses and abutting portions of said mounting at one side thereof circumferentially between said recesses; biasing means unitary with said base and having portions abutting said mounting at the other side thereof; said biasing means being constructed and arranged to press said positioning means into abutment with said mounting; said positioning means and said biasing means being integral with each other; and said aperture being of sufficient size to pass said bulb.

6. An incandescent electric lamp, comprising: a base having a lateral extension for abutting a mounting, said lateral extension including two sets of circumferentially spaced radially extending projections, said sets being in different planes and having a predetermined angular relation with each other, and said sets being integral with each other.

7. An incandescent electric lamp, comprising: a base having a lateral extension for abutting a mounting, said lateral extension including two sets of circumferentially spaced radially extending projections, said sets being in different planes and having a predetermined angular relation with each other, and one of said sets being relatively rigid and another of said sets being relatively flexible.

8. An incandescent electric lamp, comprising: a base; a lateral extension unitary with said base; said lateral extension including a positioning ele-

ment and a resilient biasing element integral with each other, and the outer end portions of said elements defining adjacent general planes substantially parallel and transverse to the axis of 5 said lamp.

9. An incandescent electric lamp, comprising: a base; a lateral extension unitary with said base; and said lateral extension including two sets of 10 projections each set comprising a plurality of radially extending projections, said sets being integral with each other, and one of said sets being flexible.

10. An incandescent electric lamp, comprising: a base; a lateral extension unitary with said base; 15 and said lateral extension including two sets of radially extending circumferentially spaced projections, said sets being constructed integral with each other from a single sheet metal stamping, one of said sets being flexible and the other set 20 relatively rigid, said sets defining different general planes and said relatively rigid set comprising three such projections.

11. An incandescent electric lamp, comprising: a base; a lateral extension unitary with said base; 25 and said lateral extension including two sets of radially extending circumferentially spaced projections, each set comprising three radially extending circumferentially spaced projections, said sets being constructed integral with each other from a single sheet metal stamping, 30 one of said sets being flexible and the other set relatively rigid, said sets defining different general planes.

12. An incandescent electric lamp, comprising: a base; a lateral extension unitary with said base; 35 and said lateral extension including two sets of radially extending circumferentially spaced projections, said sets being constructed integral with each other from a single sheet metal stamping, one of said sets being flexible and the other set 40 relatively rigid, said sets being in different general planes, the projections of one set alternating circumferentially with the projections of the other set.

13. An incandescent electric lamp, comprising: 45 a base; a lateral extension on said base; and said lateral extension including two sets of projections, each set comprising three radially extending circumferentially spaced projections, said sets being constructed integral with each other from a single sheet metal stamping, one of said sets being flexible and the other set relatively rigid, 50 said sets defining different general planes, the projections of one set alternating circumferentially with the projections of the other set.

14. An incandescent electric lamp, comprising: 55 a base having a lateral extension for abutting a mounting, said lateral extension including two sets of circumferentially spaced radially extending projections, said sets being constructed integrally from a single sheet metal stamping, and 60 said sets being in different planes and having a predetermined angular relation with each other.

15. In combination: an incandescent electric lamp having a base; a mounting for said lamp, 65 said mounting having an aperture; laterally extending positioning means unitary with said base; constructed and arranged to abut said mounting; biasing means constructed and arranged to press 70 said lateral extension into abutment with said mounting; said positioning means and said biasing means being constructed integral with each other from a single sheet metal stamping; and said aperture on the one hand and said positioning means and said biasing means on the other 75 being so constructed and arranged that at least

one of said means has portions insertable through said aperture to make bayonet connection with said mounting.

16. In combination: an incandescent electric lamp; a mounting for said lamp; said lamp having a base provided with lamp contact means; laterally extending positioning means unitary with said base, constructed and arranged to abut said mounting; biasing means constructed and arranged to press said positioning means into abutment with said mounting; said positioning means and said biasing means being constructed integral with each other from a single sheet metal stamping; and a carrier, carrying contact means constructed and arranged for detachable cooperation with said lamp contact means. 10

17. In combination: an incandescent electric lamp having a base; a reflector for said lamp; positioning means, including a lateral extension unitary with said base, constructed and arranged to register with said reflector at three circumferentially spaced points to position the direction of the axis of said lamp with respect to said reflector; biasing means constructed and arranged to press said positioning means into register with 20 said reflector; said positioning means and said biasing means being constructed integral with each other. 25

18. In combination: an incandescent electric lamp having a base; a reflector for said lamp; 30 positioning means, including a lateral extension unitary with said base, constructed and arranged to register with said reflector, at one side thereof, at three circumferentially spaced points to position the direction of the axis of said lamp with respect to said reflector; biasing means constructed and arranged to abut the other side of said 35 mounting and to press said positioning means into register with said reflector; said positioning means and said biasing means being constructed integral with each other. 40

19. In combination: an incandescent electric lamp having a base; a reflector for said lamp; 45 said reflector having an aperture; positioning means, including a lateral extension unitary with said base, constructed and arranged to register with said reflector at three circumferentially spaced points to position the direction of the axis of said lamp with respect to said reflector; biasing means constructed and arranged to press 50 said lateral extension into register with said reflector; said positioning means and said biasing means being constructed integral with each other; and bayonet connection means between said lamp and said reflector, said bayonet connection means comprising portions of at least one of said positioning means and said biasing means constructed and arranged to pass through 55 said aperture.

20. In combination: an incandescent electric lamp; a mounting having an aperture through which the bulb of said lamp is insertable; means for connecting said lamp to said mounting; said connecting means comprising a lateral extension unitary with said base and abutting said mounting at one side thereof, and resilient means unitary with said base, constructed and arranged to press said lateral extension against said mounting; said resilient means having at least a part thereof disposed at the other side of said mounting; contact means on said lamp base; and carrying means, carrying contacts cooperable with said lamp contact means, so constructed and arranged that it is movable from cooper- 70 75 80 85 90 95

ative relation while leaving said lamp connected to said mounting.

21. In combination: an incandescent electric lamp having a base; a support for said lamp; connecting means so constructed and arranged as to make bayonet connection between said lamp and said support; said connecting means comprising positioning means and biasing means, unitary with said base, and constructed integral with each other from a single sheet metal stamping; said positioning means including a portion abutting said support at one side thereof; said biasing means including a portion abutting said support at the other side thereof and being constructed and arranged to press said positioning means into abutment with said support.

22. In combination: an incandescent electric lamp having a base; a support for said lamp; connecting means making bayonet connection between said lamp and said support; said connecting means comprising positioning means and biasing means, unitary with said base, and constructed integral with each other from a single sheet metal stamping; said positioning means including a portion abutting said support at one side thereof; said biasing means including a portion abutting said mounting at the other side thereof and being constructed and arranged to press said positioning means into abutment with said support; said bayonet connecting means comprising a bayonet aperture in said support and one of said portions constructed and arranged to make bayonet connection with said aperture.

23. In combination: an incandescent electric lamp having a base; a reflector for said lamp, said reflector having a first portion extending transversely to the axis of said lamp and a second portion defining a circle about the axis of said lamp; positioning means, including a lateral extension unitary with said base, constructed and arranged to abut said first portion of said reflector at one side thereof, constructed and arranged to position the direction of the axis of said lamp with respect to said reflector, and said lateral extension having a portion disposed in and gaged by said second portion of said reflector to position said lamp laterally with respect to said reflector; biasing means unitary with said base, abutting said reflector at the other side, constructed and arranged to press said positioning means into abutment with said reflector; and said positioning means and said biasing means being integral with each other.

24. In combination: an incandescent electric lamp having a base; mounting means for said lamp, said mounting means having an aperture having a plurality of circumferentially spaced radially extending recesses; laterally extending positioning means unitary with said base, abutting said mounting at one side thereof; said positioning means including a portion disposed in and gaged by a portion of said mounting means to position said lamp laterally with respect to said mounting means; biasing means unitary with said base, having portions insertable through said recesses and abutting said mounting at the other side thereof circumferentially between said recesses, constructed and arranged to press said positioning means into abutment with said mounting; and said positioning means and said biasing means being integral with each other.

25. In combination: an incandescent electric lamp having a bulb and a base; mounting means for said lamp, said mounting means having an

aperture having a plurality of circumferentially spaced radially extending recesses; laterally extending positioning means unitary with said base, having portions insertable through said recesses and abutting portions of said mounting at one side thereof circumferentially between said recesses; said positioning means including a portion disposed in and gaged by a portion of said mounting means to position said lamp laterally with respect to said mounting means; biasing means unitary with said base and having portions abutting said mounting at the other side thereof; said biasing means being constructed and arranged to press said positioning means into abutment with said mounting; said positioning means and said biasing means being integral with each other; and said aperture being of sufficient size to pass said bulb.

26. In combination: an incandescent electric lamp having a bulb and a base; mounting means for said lamp, said mounting means having an aperture having a plurality of circumferentially spaced radially extending recesses; laterally extending positioning means on said base, having portions insertable through said recesses and abutting portions of said mounting circumferentially between said recesses; biasing means constructed and arranged to press said positioning means into abutment with said mounting; said positioning means and said biasing means being so constructed and arranged that they are unitary with said base; and said aperture being of sufficient size to pass said bulb.

27. In combination: an incandescent electric lamp having a base; a reflector for said lamp, said reflector having an aperture through which said base is insertable; laterally extending positioning means on said base, abutting said reflector at one side thereof at a plurality of circumferentially spaced points; biasing means, abutting said reflector at the other side thereof, constructed and arranged to press said positioning means into abutment with said reflector; said positioning means and said biasing means being constructed and arranged so that they are unitary with said base; and bayonet connection means between said lamp and said reflector comprising a plurality of circumferentially spaced radially outwardly extending portions on said biasing means and a plurality of circumferentially spaced recesses extending radially outward from the margin of said aperture, said bayonet connection means being so constructed and arranged that said portions are bodily insertable through said recesses by axial movement of said lamp, and by subsequent rotation of said lamp brought into abutment with said other side of said reflector as aforesaid.

28. In combination: an incandescent electric lamp having a bulb and a base; a reflector for said lamp, said reflector having an aperture through which the bulb of said lamp is insertable; laterally extending positioning means on said base, abutting said reflector at one side thereof at a plurality of circumferentially spaced points; biasing means, abutting said reflector at the other side thereof, constructed and arranged to press said positioning means into abutment with said reflector; said positioning means and said biasing means being constructed and arranged so that they are unitary with said base; and bayonet connection means between said lamp and said reflector comprising a plurality of circumferentially spaced portions on said positioning means and a plurality of circumferentially spaced recesses ex-

tending radially outward from the margin of said aperture, said bayonet connection means being so constructed and arranged that said portions are bodily insertable through said recesses by 5 axial movement of said lamp, and by subsequent rotation of said lamp brought into abutment with said side of said reflector as aforesaid.

29. In combination: an incandescent electric lamp having a base; a reflector for said lamp, 10 said reflector having an aperture; positioning means, unitary with said lamp, constructed and arranged to position said lamp with respect to said reflector; said positioning means including a lateral extension having axially extending 15 flange means so constructed and arranged that it is gaged by said aperture to position said lamp laterally with respect to said reflector and having also radial flange means extending radially outwardly from said axially extending flange means 20 and abutting a lateral face of said reflector at a plurality of circumferentially spaced points to position the direction of the axis of said lamp with respect to said reflector; and biasing means, 25 unitary with said lamp, comprising a resilient portion, abutting said reflector at the other lateral face thereof, so constructed and arranged that it is flexible in a direction toward and away from said reflector and presses said radial flange means into abutment with said reflector as aforesaid.

30. In combination: an incandescent electric lamp having a base; a reflector for said lamp, said reflector having an aperture; positioning means, unitary with said lamp, constructed and arranged to position said lamp with respect to 35 said reflector; said positioning means including a lateral extension having axially extending flange means so constructed and arranged that it is gaged by said aperture to position said lamp laterally with respect to said reflector and having 40 also radial flange means extending radially outwardly from said axially extending flange means and abutting a lateral face of said reflector at a plurality of circumferentially spaced points to position the direction of the axis of said lamp 45 with respect to said reflector; biasing means, unitary with said lamp, comprising a resilient portion, abutting said reflector at the other lateral face thereof, so constructed and arranged that it is flexible in a direction toward and away from 50 said reflector and presses said radial flange means into abutment with said reflector as aforesaid; and bayonet connection means between at least one of said positioning means and said biasing means on the one hand and said reflector on 55 the other comprising a plurality of circumferentially spaced recesses extending radially outwardly from said aperture and a plurality of circumferentially spaced projections, forming a part of at least one of said means, bodily insertable, 60 from one side of said reflector, through said recesses by axial movement of said lamp, and by rotation of said lamp brought to a position between said recesses at the other side of said reflector.

65. 31. In combination: an incandescent electric lamp having a base; a reflector for said lamp, said reflector having an aperture; positioning means, unitary with said lamp, constructed and arranged to position said lamp with respect to 70 said reflector; said positioning means including a lateral extension having axially extending flange means so constructed and arranged that it is gaged by said aperture to position said lamp laterally with respect to said reflector and having 75 also radial flange means extending radially

outwardly from said axially extending flange means and abutting a lateral face of said reflector at a plurality of circumferentially spaced points to position the direction of the axis of said lamp with respect to said reflector; biasing means, unitary with said lamp, comprising a resilient portion, abutting said reflector at the other lateral face thereof, so constructed and arranged that it is flexible in a direction toward and away from said reflector and presses said radial flange means into abutment with said reflector as aforesaid; and bayonet connection means between said biasing means and said reflector comprising a plurality of circumferentially spaced recesses extending radially outwardly from said aperture 10 and a plurality of circumferentially spaced projections, forming a part of said biasing means, bodily insertable, from one side of said reflector, through said recesses by axial movement of said lamp, and by rotation of said lamp brought to 15 a position between said recesses at the other side of said reflector.

32. In combination: an incandescent electric lamp having a base; a reflector for said lamp, said reflector having an aperture; positioning means, unitary with said lamp, constructed and arranged to position said lamp with respect to said reflector; said positioning means including a lateral extension having axially extending flange means so constructed and arranged that it is gaged by said aperture to position said lamp laterally with respect to said reflector and having also radial flange means extending radially outwardly from said axially extending flange means and abutting a lateral face of said reflector at a plurality of circumferentially spaced points to position the direction of the axis of said lamp with respect to said reflector; biasing means, unitary with said lamp, comprising a resilient portion, abutting said reflector at the other lateral face thereof, so constructed and arranged that it is flexible in a direction toward and away from said reflector and presses said radial flange means into abutment with said reflector as aforesaid; and bayonet connection means between said positioning means and said reflector comprising a plurality of circumferentially spaced recesses extending radially outwardly from said aperture 30 and a plurality of circumferentially spaced projections forming a part of said positioning means, bodily insertable, from one side of said reflector, through said recesses by axial movement of said lamp, and by rotation of said lamp brought to a 35 position between said recesses at the other side of said reflector.

33. In combination: an incandescent electric lamp having a base; a reflector for said lamp, said reflector having an aperture; positioning means, unitary with said lamp, constructed and arranged to position said lamp with respect to said reflector; said positioning means including a lateral extension having axially extending flange means so constructed and arranged that it is gaged by said aperture to position said lamp laterally with respect to said reflector and having also radial flange means extending radially outwardly from said axially extending flange means and abutting a lateral face of said reflector at a plurality of circumferentially spaced points to position the direction of the axis of said lamp with respect to said reflector; biasing means, unitary with said lamp, comprising a resilient portion, abutting said reflector at the other lateral face thereof, so constructed and arranged that it is flexible in a direction toward and away 40 from said reflector and presses said radial flange means into abutment with said reflector as aforesaid; and bayonet connection means between said positioning means and said reflector comprising a plurality of circumferentially spaced recesses extending radially outwardly from said aperture 45 and a plurality of circumferentially spaced projections forming a part of said positioning means, bodily insertable, from one side of said reflector, through said recesses by axial movement of said lamp, and by rotation of said lamp brought to a 50 position between said recesses at the other side of said reflector.

65. 34. In combination: an incandescent electric lamp having a base; a reflector for said lamp, said reflector having an aperture; positioning means, unitary with said lamp, constructed and arranged to position said lamp with respect to 70 said reflector; said positioning means including a lateral extension having axially extending flange means so constructed and arranged that it is gaged by said aperture to position said lamp laterally with respect to said reflector and having 75 also radial flange means extending radially

from said reflector and presses said radial flange means into abutment with said reflector as aforesaid; and bayonet connection means between both said positioning means and said biasing means on the one hand and said reflector on the other comprising a plurality of circumferentially spaced recesses extending radially outwardly from said aperture and a set of a plurality of circumferentially spaced projections 5 forming a part of each of said positioning means and said biasing means respectively, either set being bodily insertable, from one side of said reflector, through said recesses by axial movement of said lamp, and by rotation of said lamp 10 brought to a position between said recesses at the other side of said reflector.

34. An incandescent electric lamp, comprising: base-means; said base-means including a lateral

extension; flange means on said lateral extension, the periphery of said flange means defining a cylinder; and said base-means including also a resilient element unitary with said base-means and extending outwardly in a general plane transverse to the axis of said lamp, said resilient element being flexible in planes including the axis of said lamp. 5

35. An incandescent electric lamp, comprising: a base; and positioning means unitary with said base and including a lateral extension having axially extending flange means defining a cylindrical surface, radial flange means extending radially outwardly from said axially extending flange means, and a plurality of circumferentially spaced projections extending axially from 10 said radial flange means. 15

HARRY A. DOUGLAS.

CERTIFICATE OF CORRECTION.

Patent No. 2,117,761.

May 17, 1938.

HARRY A. DOUGLAS.

It is hereby certified that error appears in the printed specification of the above numbered patent requiring correction as follows: Page 6, second column, line 1, for the word "noncyclic" read concyclic; and that the said Letters Patent should be read with this correction therein that the same may conform to the record of the case in the Patent Office.

Signed and sealed this 5th day of July, A. D. 1938.

(Seal)

Henry Van Arsdale,
Acting Commissioner of Patents.

from said reflector and presses said radial flange means into abutment with said reflector as aforesaid; and bayonet connection means between both said positioning means and said biasing means on the one hand and said reflector on the other comprising a plurality of circumferentially spaced recesses extending radially outwardly from said aperture and a set of a plurality of circumferentially spaced projections 5 forming a part of each of said positioning means and said biasing means respectively, either set being bodily insertable, from one side of said reflector, through said recesses by axial movement of said lamp, and by rotation of said lamp 10 brought to a position between said recesses at the other side of said reflector.

34. An incandescent electric lamp, comprising: base-means; said base-means including a lateral

extension; flange means on said lateral extension, the periphery of said flange means defining a cylinder; and said base-means including also a resilient element unitary with said base-means and extending outwardly in a general plane transverse to the axis of said lamp, said resilient element being flexible in planes including the axis of said lamp. 5

35. An incandescent electric lamp, comprising: a base; and positioning means unitary with said base and including a lateral extension having axially extending flange means defining a cylindrical surface, radial flange means extending radially outwardly from said axially extending flange means, and a plurality of circumferentially spaced projections extending axially from 10 said radial flange means. 15
